UNITED STATES PATENT OFFICE.

HERBERT KIENZLE, OF NEW YORK, N. Y.

ILLUMINATED CLOCK.

1,143,632.

Specification of Letters Patent. Patented June 22, 1915.

Application filed October 28, 1914. Serial No. 368,956.

To all whom it may concern:

Be it known that I, HERBERT KIENZLE, a subject of the Emperor of Germany, residing in the city, county, and State of New York, have invented certain new and useful Improvements in Illuminated Clocks, of which the following is a specification.

This invention relates to clocks and especially to means for illuminating clocks 10 used as dormitory or bed-room clocks.

With the normal methods of illuminating bed-room clocks, the lamp is separated from the clock and positioned immediately in front of the same in which position, considerable care must be exercised not to break 15 the same when cleaning. Also in such front position, the clock must be disposed to one side of, and at the same time in front of, the dial of the clock, thus requiring a separate 20 support for the same which takes up a certain amount of space. Furthermore, the lamp when suddenly lighted in the dark will shock or jar the eye. To overcome this latter defect, shades may, of course, be used, 25 and would be required.

In view of the foregoing, it is aimed, among the main objects of this invention, to provide a means for illuminating clocks especially adapted for illuminating dormitory or bed-room clocks, which means will be completely concealed from view and thus out of danger of being injured when dusting or cleaning the clock, which means will not require a separate support, and which 30 means will be so positioned that it will properly illuminate the dial of the clock and yet not shock the eyes and at the same time not require any shades for such purpose. To this end, a translucent dial which may be 35 made of ground glass, celluloid, paper or other clear glass is arranged to form the dial or face of the clock, and there is disposed immediately behind the said dial any suitable illuminating means that may be 40 instantly controlled at the will of the operator either near the clock or any desired distance therefrom so that when the illuminating means is in operation, the light will shine through the said dial and by reason of the 45 numerals on the face of said dial being printed in an opaque color, it more readily renders the said numerals readable by reason of the contrast.

Special features of the invention are the adaptability of the same to known clocks on the market, and also the fact that the ap-

pearance of a clock will not be altered by equipping it with this illuminating means.

Other features, capabilities, and advantages of the invention will appear from the 60 subjoined detailed description of one embodiment thereof, illustrated in the accompanying drawings in which—

Figure 1 is a front elevation of a clock equipped with the present invention, certain 65 portions of the same being broken away. Fig. 2 is a side elevation of the same, certain portions being broken away; and Fig. 3 is a diagrammatic view showing the wire connection with the battery and lamp. 70

In the embodiment shown, the clockworks 1 of a clock is housed in a cylindrical casing 2 which is located in the upper portion of an upright housing 3 having a front wall 4, a rear wall 5 and two side walls 6, 6, in the 75 upper portion of which front wall 4 there is provided a circular opening 7 to receive the translucent or transparent face or dial 8 of the clock. Beneath the clockworks of such upright clocks, there is generally a free 80 useless space forming a chamber 9. In the present invention, advantage is taken of this otherwise useless chamber 9 and the illuminating means are located therein. Preferably a dry battery 10 of standard type is 85 used which has a spring contact plate 11 starting from one side of the battery and extending adjacent to the upper end thereof, and a fixed contact plate 12 extending up from the upper end of, and near the 90 other side of said battery. A strap 13 made of any suitable electric insulating material such as pasteboard, is provided of a size sufficient to slip around the middle of the battery 10 and over the spring contact plate 11. 95 The strap 13 is provided with a lamp socket 14 to accommodate a connecting portion 15 of the lamp 16, lamp socket 14 being so disposed on said strap 13 that the connecting portion 15 of the lamp will contact with the 100 spring contact plate 11 when the strap is properly positioned on said battery.

In the present instance, the cylindrical casing 2 in its lower portion near the translucent dial 8 is provided with an opening 10. 17. When the lamp is secured in position on said battery, the battery may be positioned in said chamber 9 adjacent to the wall 4, being frictionally held in such position by a flat spring 18 secured at one end 11. 19 to the rear wall 5, continuing in a resilient loop 20 disposed between the rear

wall and the battery, and the other end of said loop continuing into an elongated flat portion 21 that is disposed adjacent to the side of the battery, and terminating in a 5 bent finger portion 22 at its upper end to engage the upper edge of the battery 10. In such position, the lamp on the battery will extend through the opening 17, and be disposed just rearwardly of the lower end 10 of the dial 8.

For connecting the lamp and battery with the switch handle 23, wires are provided which are suitably covered, one wire 24 being connected to the fixed contact plate 12 15 and the other wire 25 to the socket 15 of the strap 13, the free ends of said wires 24 and 25 terminating in suitable contacts 26 and 27 respectively (Fig. 3) located in the switch handle 23, and operable by the button 28 on said switch handle. These wires 24 and 25 pass out of said chamber 9 through an opening 29 formed in the rear wall 5. The bottom of the chamber 9 is suitably closed by a base member 30 having 25 flanges 31 to engage the walls of the chamber 9 and thereby frictionally hold said base member in position, this base member also assisting to support said battery 10 in position. It is obvious that various changes and 30 modifications may be made in the details of construction without departing from the general spirit of the invention.

I claim:

1. In combination with an upright clock 35 having a housing, clockworks supported in the upper portion of said housing, there being an opening in the upper portion of said housing adjacent to said clockworks, a translucent clock dial positioned in said opening, the housing forming a chamber beneath said clockworks, a battery disposed in said chamber, a lamp connected to said battery and disposed adjacent to, and rearwardly of said dial to be lighted by said battery, and a base member for closing the bottom of said housing, said base member having flanges for engaging said housing thereby to be frictionally held in place and supporting said battery in place.

2. In combination with an upright clock 50 having a housing, clockworks supported in the upper portion of said housing, there being an opening in the upper portion of said housing adjacent to said clockworks, a translucent clock dial positioned in said opening,

the housing forming a chamber beneath said clockworks, a battery disposed in said chamber, a lamp connected to said battery and disposed adjacent to, and rearwardly of said dial to be lighted by said battery, and a flat 60 spring disposed between the housing and the battery to frictionally hold said battery in place, and a base member for closing the bottom of said housing, said base member having flanges for engaging said housing 65 thereby to be frictionally held in place and assisting in holding said battery in place.

3. In combination with an upright clock having a housing, a casing positioned in the upper portion of said housing, clockworks 70 housed in said casing, there being a transparent dial opening near the upper portion of said housing adjacent to said casing, a clock dial positioned in said dial opening, the housing forming a chamber beneath said 75 casing, there being a lamp opening in the lower side of said casing adjacent to and rearwardly of said dial, a battery disposed in said chamber, a lamp connected to said battery and extending through said lamp opening and being disposed just rearwardly 80 of the lower edge of said dial, and wires connected to said battery and lamp whereby said lamp may be lighted.

4. In combination with an upright clock 85 and housing, a casing positioned in the upper portion of said housing, clockworks housed in said casing, there being a translucent dial opening near the upper portion of said housing and adjacent to said casing, 90 a clock dial positioned in said dial opening, the housing forming a chamber beneath said casing, there being a lamp opening in the lower side of said casing adjacent to and rearwardly of said dial, a battery disposed 95 in said chamber, a lamp connected to said battery and extending through said lamp opening and being disposed just rearwardly of the lower edge of said dial, wires connected to said battery and lamp, there being 100 a wire opening through said housing through which said wires pass outwardly, and a switch handle connected to the free ends of said wires extending out of said housing by the manipulation of which handle said lamp may be lighted.

HERBERT KIENZLE.
